Andrew F. Young, Esq.(57) **CLAIM**

The ornamental design for a shoe sole, as shown and described.

DESCRIPTION

FIG. 1 is a left front perspective view of an embodiment of the present invention.

FIG. 2 is a left side elevational view of the embodiment shown in FIG. 1.

FIG. 3 is a right side elevational view of the embodiment shown in FIG. 1.

FIG. 4 is a bottom plan view of the embodiment shown in FIG. 1.

FIG. 5 is a front elevational view of the embodiment shown in FIG. 1; and,

FIG. 6 is a rear elevational view of the embodiment shown in FIG. 1.

No claim is made to the upper construction shown by use of dashed-shadow lines. The upper is shown as an environmental aid only. Identified sections of the shoe soles in multiple figures marked by dashed-shadow lines also form no part of the claimed design and are provided for environmental assistance only. No claim is made to the portion of the shoe soles not shown in solid lines, the remaining portions of the shoe sole are not claimed.
